UNITED STATES PATENT OFFICE.

HENRY C. DAVIS, OF TERRE HAUTE, INDIANA.

HYDROCARBON-BURNER.

SPECIFICATION forming part of Letters Patent No. 413,649, dated October 29, 1889.

Application filed January 19, 1889. Serial No. 296,859. (No model.)

To all whom it may concern:

Be it known that I, HENRY C. DAVIS, a citizen of the United States, residing at Terre Haute, county of Vigo, and State of Indiana, 5 have invented certain new and useful Improvements in Hydrocarbon-Heaters, of which the following is a specification.

My invention relates to hydrocarbon-heaters, whereby a hydrocarbon vapor and steam 10 are generated, mixed, and burned; and it consists of certain improvements upon the heater which forms the subject-matter of my patent, No. 388,843, dated September 4, 1888.

These improvements consist, first, in so arranging the parts of the heater that the water-heater shall be arranged out of direct contact 15 with the flame of the heater, since I have found that a more steady flame is produced when such heater is thus arranged than when the flame plays directly thereon, in which latter case the water coming in contact with the very highly-heated metal became instantaneously converted into steam, causing uneven and excessive pressure and an unsteady 20 flame.

The improvements consist, in the second place, in providing the water-heater with a filling of broken slag or analogous material, which prevents the accumulation of solid 25 matter or scale upon the interior walls of the chamber.

In the drawings, Figure 1 is a perspective view of a heater embodying my invention. Fig. 2 is a central vertical section of a burner 30 of a somewhat different construction. Fig. 3 is a detail view illustrating the operating device for the valves.

In so far as practicable, I will in this case make use of the same reference-letters for 35 analogous parts as I have in my aforesaid patent.

R and S represent, respectively, the water and hydrocarbon - fluid supply pipes, the former leading into a water-heater or vapor- 40 generator B, and the latter into the oil-retort C. The oil-retort C constitutes one end of a divided heating-casing, which is arranged directly above the burners n, while the end of this casing opposite the retort C contains a 45 superheating-chamber A, to which the hydrocarbon-vapor is led from the retort C by the pipe g. From the superheating-chamber A

the hydrocarbon gas or vapor is delivered through the conduit h to the mixing-chamber in the casing F, where it meets the steam and 55 passes thence to the burners. The steam which has been generated in the heater B is led therefrom through the pipe p to the lower portion of the mixing-chamber below the diaphragm i, passing through which it meets and 60 mingles with the hydrocarbon vapor.

T is the pan or tray situated below the burners and described and shown in my aforesaid patent.

The water-heater B, instead of being ar- 65 ranged directly above the burners, as in my patented construction, where it occupied the same position as does the superheater in the construction constituting my present invention, is arranged so that, while the flame shall 70 not come directly into contact therewith, yet it shall be sufficiently heated to cause the water which enters the heater to be converted into steam.

As shown in Fig. 2, the water-heater B is 75 cylindrical in shape, and is situated above the oil-retort and superheater.

The heater B is supported by a plug or coupling-piece D, which is preferably screw-threaded and tapped into a boss b in the 80 heater B and into the partition a, between the chambers A and C of the hydrocarbon-heater.

Instead of being arranged above the oil-retort and superheater, the water-heater may 85 be located to one side thereof, as shown in Fig. 1, the effect being the same in either case.

In ordinary water-heaters or steam-generators the presence of lime and other materials in the water results in a deposit or coating of 90 scale upon the inner surface of the heater and in a gradual deterioration of the latter. I have found that this can be prevented by placing particles of a refractory material—such as slag—in the heater, which acts as a 95 filter, the result being that the lime and other materials which form scale are deposited upon or taken up by the said refractory material rather than by the metal.

In the drawings I have shown the water- 100 retort B as filled with particles of slag E.

f designates a filling of finely-broken material placed in the lower portion of the mixing-chamber, below the diaphragm i. This

filling serves to break the current or jet of steam which, when the parts of the burner become highly heated, is otherwise apt to blow back the hydrocarbon vapor or even extinguish the flame.

1 represents an escape communicating with the steam-pipe, and preferably provided with a valve, which may be held to its seat by a spring in the usual manner. During the operation of the burner a small amount of steam may constantly pass out through the escape, the valve of which is lifted to relieve the pressure should there be a sudden increase in the amount of steam generated.

15 2 is a draw-off pipe or faucet communicating with the steam-pipe *p* below the burners, and through which the water of condensation collecting in the said pipe, and which, if allowed to remain therein, would be blown 20 through the burner and extinguish the flame, may be drawn off, as occasion may require.

It has heretofore been customary when it was desired to start the burner to saturate the material in the tray *T* with oil from a separate can; but such operation is inconvenient 25 and attended with danger, to overcome which I provide a pipe 3, leading from the oil-pipe *S*, behind the valve *W*, and extending over the tray *T*. By opening the cock 4 in this 30 pipe 3 the desired amount of oil for starting the burner can be allowed to escape into the tray before the valves *V* and *W* are operated.

The water and oil supply pipes *R* and *S* are provided, respectively, with controlling-valves 35 *V* and *W*. The stems *v* and *w* of these valves, which may be ordinary needle-valves, are provided, respectively, with arms *X* and *Y*, which arms are connected, so that they may be moved together by a link *Z*. One or both arms 40 are provided with a series of apertures *y*, arranged on a line radiating from the axis of the valve-stem, and by means of these apertures the adjustable end or ends of the link *Z* may be connected with the arm at different dis-

tances from the axis of oscillation, in order to 45 permit the relative extent of the movements of the two arms to be varied. By these means a greater or less proportion of water as compared with the amount of oil may be fed to the burner, as may be found desirable. One of 50 the arms is provided with a handle *x*, by which it is operated, the movement imparted to such arm being communicated to the other arm through the link *Z*.

The superheater as a separate chamber 55 might be dispensed with, as by leaving out the partition *a*, in which case the hydrocarbon vapor would be taken directly from the oil-retort to the mixing-chamber.

Without limiting myself to the precise construction and arrangement of parts shown, I claim—

1. In a hydrocarbon-burning apparatus, the combination of the burners, a casing divided to form a retort *C* and a superheater *A*, connected with each other by the pipe *g*, a water-heater heated by the said burners, but arranged away from immediate proximity thereto, a mixing-chamber, and the connecting-pipes between the superheater and the mixing-chamber and the water-heater and the mixing-chamber, substantially as set forth. 65 70

2. In a hydrocarbon-burning apparatus, the combination of the burners, the oil-retort *C*, and the superheater *A*, situated above the 75 burners, the pipe *g*, connecting the retort and the superheater, the water-heater arranged above the retort and superheater, and the conducting-pipes for leading the hydrocarbon vapor and the steam to the burner, substantially as set forth. 80

In testimony whereof I have signed my name to this specification in the presence of two subscribing witnesses.

HENRY C. DAVIS.
